BY *Paul Goepfert*

ATTORNEY.

UNITED STATES PATENT OFFICE.

CHARLES M. JELLIFF, OF NEW YORK, N. Y.

METALLIC SELF-BINDER FOR BOOKS.

SPECIFICATION forming part of Letters Patent No. 228,642, dated June 8, 1880.

Application filed August 27, 1879.

To all whom it may concern:

Be it known that I, CHARLES M. JELLIFF, of the city, county, and State of New York, have invented certain new and useful Improvements in Metallic Self-Binders for Memorandum-Books, &c., of which the following is a specification.

In the accompanying drawings, Figure 1 represents an end view of my improved self-binder for books; Fig. 2, a horizontal section of the same on line *x x*, Fig. 1; and Fig. 3 is a detail vertical transverse section, showing the connection of the metallic binder and book on line *y y*, Fig. 2.

Similar letters of reference indicate corresponding parts.

This invention relates to an improved metallic self-binder for memorandum and other books, by which the book, tablet, or pad may be quickly inserted or removed and firmly retained when in proper position.

The invention consists of a metallic binder that is made **U** shape with rectangular sides, having inwardly-bent lap-edges or lips. The book is inserted at the end of the binder and retained by the lips, which bear on the stitches, projecting at both sides of the book.

Referring to the drawings, A represents the cover of a memorandum or other book; B, the self-binder, and C the book, pad, or tablet that is to be inserted into the binder. The self-binder B is of metal, and bent in the shape of the letter **U**, the sides being at right angles to the middle portion or back. The edges of the sides are bent inwardly, so as to form

lap-edges or lips *a a*. The binder B is riveted or otherwise attached to the cover A, the fastening device being covered or not, as desired.

The book is stitched in such a manner that the stitches form raised ribs *b b* at both sides, 40 which are engaged by the lips *a a*, so that the book cannot get detached from the binder in transverse direction, but can only be removed therefrom by being pushed out in longitudinal direction.

When the book or pad is used up it is removed and a new one inserted in its place, the binder facilitating thus in a very simple manner the exchanging of the books.

Having thus described my invention, I claim 50 as new and desire to secure by Letters Patent—

The combination of a metallic self-binder, B, having its sides bent at right angles to the back, and provided with inwardly-bent lips *a a*, with a book, tablet, or pad, C, having projecting stitches *b b* at both sides of the book, so as to form contact with the lips and prevent the detaching of the book from the binder in transverse direction, but admit its removal 60 and insertion in longitudinal direction, substantially as and for the purpose described.

In testimony that I claim the foregoing as my invention I have signed my name, in presence of two witnesses, this 23d day of August, 65 1879.

CHARLES M. JELLIFF.
